CHRISTMAS TREE HOLDER

Harry F. Mitchell and Oscar L. Gilbert,
Mineral Wells, Tex.

Application March 26, 1948, Serial No. 17,326

1 Claim. (Cl. 248—44)

1

Our invention relates to holders for supporting a stem, such as the stem of a Christmas tree, vertically relative to a supporting surface.

With the foregoing in view, an object of our invention is to provide an improved holder of the class described.

A further object is to provide an improved holder of the class described which is readily demountable into its component parts for storage and/or shipment.

A further object is to provide an improved holder of the class described which is readily and efficiently made of low-priced material and which is capable of being assembled by unskilled personnel.

A further object is to provide an improved holder of the class described which is self-adapting to slightly tilted or uneven surfaces, whereby the supported stem is maintained vertically even though the supporting surface is not precisely horizontal.

Other objects and advantages reside in the particular structure of the invention, combination and arrangement of the several parts thereof, and will be readily understood by those skilled in the art upon reference to the attached drawing in connection with the following specification, wherein the invention is shown, described and claimed.

In the drawing:

Figure 1 is a plan view of the holder according to the invention;

Figure 2 is an elevational view thereof;

Figure 3 is a transverse vertical sectional view taken substantially on the plane of the line 3—3 of Figure 1;

Figure 4 is a horizontal sectional view taken substantially on the plane of the line 4—4 of Figure 2;

Figure 5 is a transverse vertical sectional view taken substantially on the plane of the line 5—5 of Figure 1.

Referring specifically to the drawing, wherein like reference characters have been used throughout the several views to designate like parts, the holder according to the invention includes a socket 10 which is adapted to be vertically disposed on any suitable horizontal supporting surface, such as the floor of a room. The socket 10 is of hollow tubular configuration and is preferably non-circular, wherein to provide a plurality of side walls 11 lying in vertical planes in angular relation to each other. Preferably, the socket is made of sheet material, such as sheet metal, whereby it will be slightly yieldable upon

2

the insertion of a substantially cylindrical stem of slightly over size relative to the interior diameter of the socket therein. In the embodiment shown, the socket 10 is square in cross-section and defined by four sides 11. To support the socket 10 vertically on a horizontally-disposed supporting surface, there is provided a plurality of feet which are generally indicated at 12 and which preferably correspond in number to the number of sides of the socket. In this case, obviously, the number of feet is four, and each foot comprises a foot portion proper 13 of sheet material and an upwardly-turned leg 14 which lies along the exterior of the lower portion of each side 11 of the socket. If desired, the marginal portions of the feet 12, including the foot portions 13 and leg portions 14, may be inwardly turned to provide double thicknesses, as indicated at 15, whereby to increase the inherent resiliency of the parts. It should be noted at this time that the angle at which the foot portions 13 join the leg portions 14 is slightly greater than a right angle, whereby the foot portions 13 normally depend slightly below the lower edge of the socket 10, as indicated in broken lines, Figure 2. With this arrangement, when the weight of the Christmas tree or the like is borne by the socket, the feet 13 flex upwardly to conform to the slope of the surface. Thus, if the surface is not exactly horizontal, nevertheless the foot portions 13 will lie flatly thereagainst while the socket 10 is enabled to extend vertically. The leg portions 14 of the feet 12 are secured to the socket 10 by pairs of bolts 16 extending through the parts and which are vertically spaced above the plane of the foot portions 12, whereby to provide a lower portion of each leg portion which is adapted to be flexed with the foot portions when the same are conforming to an irregular supporting surface. Suitable reinforcing struts 17 extend between the foot portions 13 and the leg portions 14 of each foot, whereby to resist flexing of the same. At the same time, the struts 17 permit sufficient flexing to allow the bottom edge of the socket and the under surface of the foot portions 13 to be flatly seated upon a supporting surface.

The struts 17 are preferably attached to the feet 12 by welding or soldering, or the like, whereby to form an integral structure therewith. However, we prefer to connect the feet 12 to the socket 10 by means of bolts, whereby the same may be readily knocked down for storage between the Christmas seasons.

Moreover, while we have shown and described

what is now thought to be a preferred embodiment of the invention, it is to be understood that the same is susceptible of other forms and expressions. Consequently, we do not limit ourselves to the precise structure shown and described hereinabove, except as hereinafter claimed.

We claim:

A Christmas tree stand, comprising an up-standing rectangular tubular socket having flat substantially vertical sides, L-shaped feet for connection with the socket to maintain the same upright, each of the L-shaped feet including a substantially vertical flat web contacting the outer face of one flat side of the socket and a substantially horizontal flat elongated web to engage the floor or the like and extending radially from the socket, bolts detachably connecting the substantially vertical webs with the sides of the socket, and vertically disposed diagonal reinforcing plates, connecting the substantially vertical and

substantially horizontal webs, the substantially horizontal webs being somewhat resilient and being arranged at angles slightly greater than right angles with respect to the substantially vertical webs.

HARRY F. MITCHELL.
OSCAR L. GILBERT.
